JUSTIFYING SPACEBAND

George W. Allison, St. Albans, N. Y., assignor
to Mergenthaler Linotype Company, a corpora-
tion of New York

Application November 17, 1937, Serial No. 174,960

18 Claims. (Cl. 199—68)

This invention relates to justifying spacers or spacebands, such as are used in the typographical composing and casting machines known commercially under the trade-mark "Linotype", and kindred machines, for the justifying of composed lines of matrices prior to the casting operations.

These spacers or spacebands are ordinarily formed of two main parts, viz., two oppositely wedge-shaped members, one shorter than the other and known as the stationary part and provided with ears by which it is held against movement during justification, and the second or longer member which is slidably connected (by tongue and groove portions) to the shorter one in such manner as to enable it to be forced upwards through the composed line for effecting the justification.

Heretofore, the tongue and groove portions of the spacebands have been employed to perform the dual function of guiding the members in their relative movement and holding them against facewise movement. Due to the smallness of the tongue and groove portions, however, it has been impractical to machine the surfaces thereof by grinding, and although with very careful milling operations a workable spaceband can be manufactured, it lacks a completely satisfactory close fit of the tongue and groove which, at the same time, will not unduly impede the sliding action of the members in their relative movement. Moreover, the fit of the tongue and groove obtained by milling is not accurate enough to obviate to a desirable extent a relative edge-wise movement of the members, which tends to cause binding and results in excessive wear of the parts and a material shortening of the life of the spaceband.

According to the present improvements, the wedge-shaped members are formed for sliding engagement with bearing and guiding surfaces which are machine-ground throughout their full extent, and in carrying out the invention, the spaceband is preferably made in three separate parts adapted for assembly after the bearing and guiding surfaces have been properly finished. However, in its completely assembled form, the spaceband may or may not retain its three-part character, according to whichever of three embodiments thereof it is desired to produce.

According to one embodiment of the invention, the shorter wedge-shaped member is formed on its inner surface with a raised guiding block adapted to fit in a slot formed in the longer member, and a small removable section, having a tight tongue and groove connection with the block and

a relatively loose tongue and groove connection with the longer member, is employed to function solely to hold the members against facewise movement.

Another embodiment of the invention provides a spaceband wherein the section for holding the members against facewise movement is made as a separate part and subsequently attached permanently to the guiding block by spot-welding.

A third embodiment of the invention, on the other hand, provides a spaceband wherein the guiding block is formed separately and then permanently attached to the shorter wedge-shaped member by spot-welding, the block being formed with integral laterally extending tongues for effecting the sliding connection of the two members which holds them against facewise movement.

Referring to the drawings, which shows the parts of the spaceband on a greatly enlarged scale,

Fig. 1 is a face view, showing the shorter member in its uppermost position by the solid lines and in its lowermost position by the dotted lines;

Fig. 2 is a longitudinal section taken on the line 2—2 of Fig. 1;

Fig. 3 is a perspective view of the shorter member, showing its inner face which is adapted for bearing contact with the longer member;

Fig. 3^a is a perspective view of the removable section detached;

Fig. 4 is a horizontal section taken on the line 4—4 of Fig. 1;

Fig. 5 is a horizontal section taken on the line 5—5 of Fig. 1;

Figs. 6 and 6^a are views similar to Figs. 3 and 3^a, showing a different embodiment of the invention; and

Figs. 7 and 7^a are views similar to Figs. 3 and 3^a, showing still another embodiment of the invention.

A spaceband of the kind referred to comprises two wedge-shaped members A and B secured together for relative slidable movement, the shorter member A being provided with ears A¹ 45 by which it is held against vertical movement during justification. The member A is machine-ground to a good finish along its marginal portions a to provide a plane surface for sliding contact with the member B; and in its lower portion, intermediate the marginal surfaces, it is formed with a raised portion A² cooperating in a manner hereinafter described with the longer member B to guide the members in their relative movement.

The longer wedge member B has formed in it a longitudinal slot or recess B¹ terminating just short of the upper end of the member and extending entirely through the member except in the lower portion or thick end of the wedge. Here too, the member B, to provide a plane surface for contact with the member A, is machine-ground to a good finish along its marginal portions b contiguous to the slot B¹. The slot B¹ is adapted to receive the raised portion A² of the shorter member and cooperate with it to guide the members in their relative sliding movement during justification.

In the new and improved construction, according to the embodiment shown in Figs. 1 to 5, the raised portion A² is formed with straight machine-ground edge walls A³ perpendicular to the inner surface of the member A. The raised portion A² is also formed with a transverse slot A⁴ whose upper and lower walls are shaped as at A⁵ to accommodate a removable section A⁶ adapted to fit slidingly in the slot, its correspondingly shaped opposite edges A⁷ having a tight dovetail fit with the undercut walls A⁵. The section A⁶ is wider than the raised portion A² so that its bevelled opposite edges A⁸ project beyond the opposite edges of the raised portion A².

The slot B¹, in the long wedge member B, is defined by edge walls B² which, for a given depth, extend perpendicularly to the bearing surfaces b on opposite sides of the slot B¹ and then flare outwardly as at B³, the edge walls B² being machine-ground for an accurate sliding engagement with the edge walls A³ of the raised portion A², and the flared portions B³ being adapted to cooperate with the bevelled edges A⁸ of the removable section A⁶. Since the bevelled edges A⁸ of the section A⁶ can be machine-ground to correspond accurately with the bevelled surfaces B³, facewise play between the members A and B is minimized, it being noted, however, that these surfaces need not be finished for sliding engagement because during justification the inward pressure on the outer surfaces of the members A and B tends to separate the bevelled surfaces A⁸ and B³, all guiding being cared for by the machined surfaces A³ and B².

During assembly of the parts, the raised portion A², with the section A⁶ in place, is slid into the slot B¹ from the open or lower end thereof in order to establish the interfitting or dovetail connection, the member B being provided with a pin B⁴ adjacent its lower end which acts as a stop for the member A and thus prevent the parts from sliding apart longitudinally when in use, all in the usual manner.

In the second embodiment of the invention shown in Figs. 6 and 6^a, the section A⁶ (as before) is formed as a separate element to permit the grinding of the bearing and guiding surfaces a and A³ on the member A and raised portion A², respectively, but is thereafter spot-welded in place in the slot A⁴ formed in the raised portion A² and thus irremovably attached to the member A. In this instance, the walls A⁵ of the slot A⁴ and the side edges A⁷ of the section A⁶ are straight (rather than dovetailed) and cooperate to locate the section A⁶ accurately for the welding operation.

According to the third embodiment of the invention shown in Figs. 7 and 7^a, a rectangular block A⁹ (corresponding to the raised portion A² of the first and second embodiment) is adapted to be spot-welded to the shorter wedge-shaped member A after the bearing surfaces a of the

member and the guiding surfaces A³ of the block A⁹ have been machine-ground. In this instance, laterally extending tongues A¹⁰ and A¹¹, adapted to engage the surfaces B³ on the longer member B to hold the members against facewise movement, are formed integrally with the block A⁹, since they do not interfere with the machine-grinding of the guiding surfaces A³ before the block A⁹ is welded to the member A.

The improved spaceband presents many advantages over the old. For example, the bearing and guiding surfaces are all machine-ground, providing accurate fitting and engagement of the parts, a smooth and easy sliding of the parts in their relative movement, and an appreciable reduction of relative facewise and edgewise movement of the parts, all of which greatly reduces wear and increases the life of the spaceband. By building up the spaceband of three separate parts, all surfaces of the parts which are adapted for sliding contact when assembled are readily accessible for machine-grinding to provide smooth finished surfaces, just enough tolerance being allowed to provide freedom of movement of the members without interfering with the accurate guiding of the members in their relative movement. Moreover, the members A and B can be standardized, thus rendering corresponding parts interchangeable and thereby materially reducing cost, both as regards original manufacture and repair of parts. Furthermore, the behavior of the new spaceband in use is far superior to that of the old, due to the machine-grinding of all bearing and guiding surfaces which slide upon each other smoothly and easily as the spaceband is expanded during justification.

In the accompanying drawings, the invention has been shown merely by way of example and in preferred form and obviously many variations and modifications may be made therein which will still be comprised within its spirit. It should be understood, therefore, that the invention is not limited to any specific form or embodiment except insofar as such limitations are specified in the appended claims.

Having thus described my invention, what I claim is:

1. A justifying spaceband including, in combination, a pair of relatively movable wedge-shaped members presenting inner surfaces in facewise bearing contact and other surfaces in edgewise contact for guiding the members in their relative movement, and a free-fitting connection between said members acting solely to hold them against facewise movement.

2. A justifying spaceband including, in combination, a pair of relatively movable wedge-shaped members presenting inner surfaces in facewise bearing contact and surfaces perpendicular thereto in edgewise contact for guiding the members in their relative movement, and a free-fitting connection between said members acting solely to hold them against facewise movement.

3. A justifying spaceband including, in combination, a pair of relatively movable wedge-shaped members presenting inner surfaces in bearing contact, interfitting means presenting machine-ground surfaces in sliding contact for guiding the members edgewise in their relative movement, and a free-fitting connection between said members acting solely to hold them against facewise movement.

4. A justifying spaceband including, in combination, a pair of relatively movable complementary wedge-shaped members presenting machine-

ground inner surfaces in bearing contact, a raised guiding portion carried on the inner surface of one member and presenting edge walls perpendicular to the inner wall of said member and adapted for sliding engagement with the edge walls of a slot formed in the other member to guide the members in their relative movement, and a free-fitting connection between said members acting solely to hold them against facewise movement.

5. A justifying spaceband including, in combination, a pair of relatively movable wedge-shaped members presenting inner surfaces in bearing contact, one member being formed on its inner surface with a raised guiding portion having machine-ground edge walls, and the other member being formed with a slot to receive said raised portion, the walls of the slot being machine-ground and having a sliding engagement with the 10 edge walls of the raised portion, and a free-fitting connection between said members acting solely to hold them against facewise movement.

6. A justifying spaceband including, in combination, a pair of relatively movable complementary wedge-shaped members presenting inner surfaces in bearing contact, one member being formed on its inner surface with a raised guiding portion and the other member being formed with a slot slidably fitted to the raised guiding 15 portion, and a separate section having opposite bevelled edges projecting beyond the side edges of the raised guiding portion on the one member and engaged with correspondingly bevelled surfaces extending laterally from the edges of the 20 slot in the other member to hold the members against relative facewise movement.

7. A justifying spaceband including, in combination, a pair of relatively movable complementary wedge-shaped members presenting inner surfaces in bearing contact, one member being formed on its inner surface with a raised guiding portion the edge walls of which present straight guiding surfaces, and the other member being formed with a straight-sided slot slidably fitted 25 to the raised guiding portion, and a separate section having opposite bevelled edges projecting beyond the edge walls of the raised guiding portion of the one member and engaged with correspondingly bevelled surfaces extending laterally from the edges of the slot in the other member to hold the members against relative facewise movement.

8. A combination according to claim 7, wherein the separate section is removably attached to the 30 raised guiding portion.

9. A combination according to claim 7, wherein the separate section is spot-welded to the raised guiding portion.

10. A combination according to claim 7, wherein 35 in the edge walls of the raised portion extend from and are perpendicular to the inner bearing surface of the member on which the raised guiding portion is formed.

11. A justifying spaceband including, in combination, a pair of relatively movable complementary wedge-shaped members presenting inner surfaces in bearing contact, one member being formed on its inner surface with a raised guiding portion the edge walls of which present straight 40 guiding surfaces, and the other member being formed with a straight-sided slot slidably fitted to the raised guiding portion, and a separate section arranged in the raised guiding portion and having opposite bevelled edges projecting beyond the 45 guiding surfaces of said portion and overlying

correspondingly bevelled surfaces extending laterally from the straight walls of said slot to hold the members against facewise movement.

12. A justifying spaceband including, in combination, a relatively short wedge-shaped member formed on one face with a centrally located raised portion having straight machine-ground edge walls to form guiding surfaces, the face of said member on opposite sides of the raised portion being machine-ground throughout its extent to form bearing surfaces, a second longer wedge-shaped member formed with one face machine-ground for bearing contact with the bearing surfaces of said short member and having a central longitudinal slot to receive said raised portion formed on the shorter member, the edge walls of said slot being machine-ground for sliding engagement with the guiding surfaces of said raised portion, and a separate section carried by the shorter member and cooperative with the longer member solely to hold the members against facewise movement.

13. A justifying spaceband including, in combination, a relatively short wedge-shaped member formed on one face with a centrally located raised portion having straight machine-ground edge walls to form guiding surfaces, the face of said member on opposite sides of the raised portion being machine-ground throughout its extent to form bearing surfaces, a transverse slot formed in said raised portion and presenting upper and lower walls, a separate section adapted to be accommodated in said slot and having its upper and lower edges formed for engagement with the upper and lower walls of the slot, said section having machine-ground bevelled side edges projecting beyond the opposite guiding surfaces of said raised portion, a second longer wedge-shaped member formed with one face machine-ground for bearing contact with the bearing surfaces of said short member and having a central longitudinal slot to receive said raised portion formed on the shorter member, the side edges of said slot being machine-ground for sliding engagement with the guiding surfaces of said raised portion, and correspondingly shaped surfaces extending laterally from the side edges of said slot to cooperate with the bevelled projecting edges of said section, whereby said members are free to partake of a smooth and easy sliding motion while being held against facewise displacement.

14. A justifying spaceband including, in combination, a pair of relatively movable complementary wedge-shaped members presenting inner surfaces in bearing contact, means for guiding the members edgewise in their relative movement, and a removable section carried by one of said members and engaged with the other member to hold the members against facewise movement.

15. A justifying spaceband including, in combination, a pair of relatively movable complementary wedge-shaped members presenting inner surfaces in facewise bearing contact, a separate pre-formed block fixed to one member and presenting parallel guiding surfaces perpendicular to the inner surface thereof, a slot formed in the other member and presenting edge walls having parallel guiding surfaces perpendicular to the inner surface of the member and adapted for 60 edgewise contact with the parallel surfaces of said block, and means for holding the members against facewise movement.

16. A justifying spaceband including, in combination, a pair of relatively movable comple- 65

mentary wedge-shaped members presenting machine-ground inner surfaces in facewise bearing contact, a separate pre-formed block fixed to one member and presenting machine-ground edge walls perpendicular to the inner surface thereof, a slot formed in the other member and presenting parallel edge walls having machine-ground surfaces perpendicular to the inner surface of the member and adapted for edgewise contact with the parallel edge walls of said block for guiding the members in their relative movement, and means for holding the members against facewise movement.

17. A justifying spaceband according to claim 16, wherein the means for holding the members

against facewise movement comprises laterally extending tongues formed on said block and adapted to fit in grooves formed in the edge walls of said slot.

18. A justifying spaceband according to claim 4, characterized by the fact that the free-fitting connection therein referred to is constituted by bevelled tongues extending laterally beyond the opposite edge walls of the raised guiding portion carried by the one member and cooperating bevelled surfaces extending laterally from the opposite edge walls of the slot formed in the other member.

GEORGE W. ALLISON. 15
